UNITED STATES PATENT OFFICE.

CHANCY R. PIERCE, OF DUVALL, OHIO.

FODDER-BINDER.

No. 828,900.

Specification of Letters Patent.

Patented Aug. 21, 1906.

Application filed September 28, 1905. Serial No. 280,478.

To all whom it may concern:

Be it known that I, CHANCY R. PIERCE, a citizen of the United States, residing at Duvall, in the county of Pickaway, State of Ohio, have invented certain new and useful Improvements in Fodder-Binders; and I do hereby declare the following to be a full, clear, and exact description of the invention, such as will enable others skilled in the art to 10 which it appertains to make and use the same.

This invention relates to fodder-binders.

One object of the invention is to provide a simple, inexpensive, durable, and efficient frame for the compressing and binding of 15 fodder.

Another object of the invention resides in the provision of a frame provided with means for supporting and compressing the sheaves, 20 whereby the latter may be bound intermediate their ends or bound at their respective ends.

With these and other objects in view the present invention consists in the combination 25 and arrangement of parts, as will be hereinafter more fully described, shown in the accompanying drawings, and particularly pointed out in the appended claims, it being understood that changes in the form, proportion, 30 size, and minor details may be made within the scope of the claims without departing from the spirit or sacrificing any of the advantages of the invention.

In the drawings, Figure 1 is a perspective 35 view of a binder. Fig. 2 is a detail perspective view. Fig. 3 is a detail elevation. Fig. 4 is a sectional view of the twine-box. Fig. 5 is a detail perspective view of a modification. Fig. 6 is an elevation of a modified form of 40 compressor with the beam in section. Fig. 7 is a view showing a part of the beam in top plan, parts of the compressor-arms being broken off and the pivotal mounting of the arms being illustrated, said figure having reference to the modified structure. Fig. 8 is a 45 perspective view of another form of compressor.

Referring now more particularly to the accompanying drawings, it will be seen that 50 two supporting-frames are arranged in spaced relation, each frame being the same in construction as the other, in view of which but one frame will be described.

The reference characters 1 and 2 designate 55 the supporting-legs of one frame, connected at their upper ends by a cross-piece 3, pro-

vided with a semicircular recess 5 midway of the legs for the reception of a tubular or other beam 6, which beam 6 connects the respective frames. It will be observed that the legs 60 1 and 2 of the frame diverge downwardly, with their lower ends connected by a brace 7, whose free ends are turned upwardly, as at 8, there being a suitable rivet 9 piercing the upwardly-turned ends 8 of the cross-piece 7 65 and the lower ends of the legs 1 and 2.

Disposed upon the top of each frame is a bracket 11, whose ends are directed upwardly and outwardly, as indicated by the reference character 12, there being a semicircular recess 13 formed in the body portion of the bracket intermediate its upwardly-turned ends corresponding with the aforesaid recess 5 of the upper cross-piece 3 of each frame for engagement with the upper surface 70 of the tubular or other member 6. It will thus be seen that the semicircular recesses 5 and 13 form a circular bearing for the respective ends of the beam 6, and reference to the drawings will disclose that each bracket 11 is 75 disposed upon the upper member 3 of the corresponding frame by means of suitable rivets 14.

There are times when the supporting-frame should be adjusted toward or away 80 from each other, and in order to permit such adjustment of the supporting-frame with respect to the beam 6 I provide a suitable set-screw 15', which works through a perforation in the recess 5 of the upper member 3 of each 85 frame for binding engagement with the beam 6. It is obvious, therefore, that if the set-screw 15' of each frame be loosened with respect to the beam 6 the frames may be readily adjusted along the latter and that when 90 the frames have been disposed in the position desired with respect to the beam they may be tightened by a proper manipulation of the set-screws 15'.

When it is desired to husk the corn, the 100 sheaves are placed upon the brackets of the supporting-frames, it being understood that the frames support the sheaves at their ends. When the sheaves are so disposed, husking can be accomplished without causing the 105 husker to bend over to a considerable extent, if at all. A suitable clamp comprising arms 16 and 17 is mounted for adjustment upon the beam 6 and designed for compressing the fodder intermediate its ends during the 110 husking operation. These arms 16 and 17 are of spring material, and it will be seen that they

are substantially semicircular and that their upper ends 18 are directed outwardly from each other with their lower ends secured in any suitable manner to a ring 19, which fits 5 the beam 6. A suitable set-screw 20 pierces the ring 19 of the compressor-frame to secure the arms of the latter in proper position with respect to the frame and the fodder to be compressed. It will thus be seen that by reason 10 of the arms 16 and 17, into which the fodder is sprung, the fodder cannot become accidentally displaced with reference to the brackets 11 of the supporting-frame.

After the husking operation has been accomplished 15 it is customary to bind the fodder intermediate its ends, and I therefore provide a suitable box or receptacle 21 upon the leg 2 of one of the supporting-frames for the reception of a ball of twine 22, which may 20 be drawn through an opening 23 in the leg 2 and over and through an eye 24, depending from the beam 6. It will thus be seen that the cord is at hand for binding purposes and that it may be readily wrapped around the 25 fodder intermediate its ends or adjacent the compressor-frame, when the fodder may be removed from the latter, as well understood. It might be stated that the eye 19 of the compressor-frame is of such size as to permit it 30 being slipped over the cord-eye 24 of the beam 6, so that the compressor-frame may be disposed at either end of the beam 6 in the event that compression is desired at one or both ends of the fodder.

35 In Fig. 5 there is shown a modified form of bracket *a*. This bracket *a* is secured to the frame *b* in the same manner as in the arrangement heretofore described. However, in form *a* it will be seen that the end *c* is curved 40 upwardly, with its extremity substantially over the body portion of the bracket, whereby husking will not tend to displace the sheaves or fodder over the brackets. This bracket *a* is provided with suitable braces *d*, 45 which converge toward the beam *e*, to which they are secured in any suitable manner.

In Figs. 6 and 7 there is shown a modified 50 form of compressor. In this instance the compressor-arms *g* and *h* are formed separately and are pivotally connected for independent movement with respect to the beam *p*, upon which they are supported. The arms each have a laterally-directed handle member *q*, adapted to contact with each other 55 when the arms are binding the fodder, and in order to prevent the arms and their handle members from moving away from each other

I provide the arm *g* with a series of notches *g'* for engagement by the dog *h'* of the spring member *h*', secured at its inner end in any 60 suitable manner to the arm *h*. In Fig. 8 there is shown still another form of compressor. In this latter form the arms *j* and *k* are formed of a single piece of material with their extremities designed to overlap each 65 other, as shown. The single piece of material of which the arms *j* and *k* are formed encircles the beam *l* and has connected with its bight portion *m* a depending arm *n*, provided with a foot portion *o*, upon which pressure 70 may be placed to cause a compression of the fodder. In other words, pressure upon the foot *o* of the arm *n* will cause the arms *j* and *k* to bind against the fodder according to the pressure upon said foot *o*. 75

What is claimed is—

1. A device of the character described comprising supporting-frames, a beam connecting the upper ends of the frames and having an eye intermediate its ends, a bracket engaging the beam directly over each of said frames for the support of the ends of the fodder, a compression-frame disposed upon the said beam intermediate said frames, and a receptacle disposed upon one of the frames 85 for the reception of a ball of twine for passage through said eye for binding the fodder together.

2. A device of the character described comprising spaced frames, a beam connecting the frames and adjustably mounted with respect thereto, the said beam having an eye intermediate its ends, a bracket engaging the end of the said beam directly over each frame and secured to the latter, compression means disposed upon the beam intermediate the said frames, said means being mounted for adjustment along said beam, and a receptacle connected with one of said frames for the reception of twine for passage through the aforesaid eye of the beam for the binding of the fodder together. 95

3. A device of the character described comprising frames, a beam adjustably connecting the frames, a bracket engaging the beam over each frame and secured to the latter, and compression means disposed upon said beam intermediate said frames. 100

In testimony whereof I affix my signature in presence of two witnesses.
